UNITED STATES PATENT OFFICE.

AUGUSTE P. CLAUDE, OF CANTON, OHIO.

DESIGN FOR A CAN.

SPECIFICATION forming part of Design No. 31,079, dated June 27, 1899.

Application filed April 12, 1899. Serial No. 712,803. Term of patent 14 years.

To all whom it may concern:

Be it known that I, AUGUSTE P. CLAUDE, a resident of Canton, in the county of Stark and State of Ohio, have invented and produced a new and original Design for Cans, of which the following is a specification, reference being had to the accompanying drawings, forming a part thereof.

Figure 1 is a side elevation. Fig. 2 is a vertical section.

As shown in the drawings, the leading or material features of my design consist in the uniform design of the can-body 1 and in the annular flange formed at the top of the can 15 and the flaring opening or mouth thereof.

The can 1 is provided with the annular flange 2, which annular flange is provided with the plain and smooth top face 3, extending from the inner periphery of the opening or 20 mouth 4 to the outer edge or periphery of the flange, and said flange being provided with the straight under edge 5, said straight under

edge being parallel with the top or upper face of said flange. The opening 4 tapers from the top of the flange 2 to the point 6, which 25 forms the bottom of the mouth. From the point 7 a vertical portion 8 is formed, which vertical portion extends from the bottom or under side of the flange 2 to the curved portion 9 of the can, said curved portion being 30 continued downward, as illustrated in the drawings.

Having thus fully described my invention, what I claim as new, and desire to secure by Letters Patent, is—

The design for a can as herein shown and described.

In testimony that I claim the above I have hereunto subscribed my name in the presence of two witnesses.

AUGUSTE P. CLAUDE.
